UNITED STATES PATENT OFFICE.

FRED M. OPITZ, OF MILWAUKEE, WISCONSIN, ASSIGNOR TO OPITZ MANUFACTURING COMPANY, OF MILWAUKEE, WISCONSIN, A CORPORATION OF WISCONSIN.

METHOD OF MAKING RADIATOR CORES.

Application filed November 9, 1922. Serial No. 599,792.

My invention relates to automobile radiators and the like, and more particularly it relates to the method or process of manipulating the sheet metal of which the radiator core is constructed, and the structure resulting therefrom.

The radiator made by my present invention is covered by my prior Patent No. 1,404,160 of January 17, 1922, upon which the present invention is an improvement.

The present application covers certain matter divided out of the application for the above patent and certain new matter as will be apparent from inspection.

The fundamental idea involved in the present invention is to convert a flat strip of sheet metal, preferably brass, copper or bronze, into a suitably formed half tube of the type disclosed in my prior patent, with a minimum of operation, and with a minimum of punishment or working of the metal.

I have devised a way of doing this by certain steps which will be disclosed in detail and claimed herein, and I have devised means for performing the steps, which means is disclosed in detail and claimed in my copending application, Serial No. 638,698, filed May 14, 1923.

The finished radiator is made up of strips or sheets all of which are active, that is, form a wall between the water to be cooled and the air outside. These strips or sheets have integral loops along their edges, front and rear, the purpose of which loops is first to space the sheets properly and to hold them together in proper relation, second to aid in the dissipation of heat, and third, to form an ornamental and protective front for the water tubes.

The water tubes have integral lateral wings or pockets which are formed in register with these loops aforementioned. These wings or pockets which I may term "water legs" provide additional surface for water cooling and they also aid in breaking up the air streams and give an improved appearance to the radiator, all as explained in my prior patent above referred to.

There is a peculiar relation between the marginal loops and the lateral wings or projections on the tube. The flat strip or sheet from which each side of a tube is formed is of very thin stock. It should not be stretched to any appreciable degree and in constructing the radiator of my invention [I have so

related the loops and the lateral wings or projections that the same amount of metal in linear length is taken up by each, that is, the loops and the projections. At the same time, provision must be made for depressing the central longitudinal part of the strip to form a trough. This trough forms one-half of the tube.

According to the preferred procedure, I first corrugate or form ridges in the sheet transversely preferably in the exact form of the finished loops. This may of course be varied, but I find it to be highly advantageous in order to set originally and thereafter to preserve the correct pitch of the ornamental loops and of the water legs or lateral projections.

After the initial corrugating or ridging which may be done by corrugating rolls as I shall elsewhere explain, the corrugations are slit in a direction longitudinal with respect to the strip and transverse with respect to the ridges, along the margins to delimit or demarcate the loops from the body of the tube. This operation is preferably performed in a punch press by means of suitable dies.

The third stage is to depress the central longitudinal part of the strip to form a gutter or trough for the tube half. This third stage is preferably performed simultaneously with a fourth stage or operation, namely, the pinching together of the corrugations or transverse ridges between the slit marginal portions which form the loops. There is a peculiar relation between the formation of the gutter or trough and the pinching of the corrugations to form the lateral wings or water legs of the finished tube. As the central longitudinal part is depressed the outer ends of the transverse ridges or corrugations are pinched together to a greater extent than are the inner or central parts which overlie the bottom of the gutter or groove. It is a well known fact that a transverse rib or corrugation of sheet metal cannot well be bent across the corrugation without distortion of the corrugation or stretching of the metal.

I have avoided the difficulty by pinching the metal together at the edges and therefore determining the line of the transverse bend where the pinching together begins. This pinching together is graduated from the outer edges of the corrugation to the line of the bend of the corrugation.

The above named operations of pinching the slit edges of the corrugations and forming the bend may be performed in a punch press by suitable dies.

5 The final and exact shaping of the lateral wings or water legs may be performed in a subsequent operation also in a punch press by suitable dies.

10 The punch press operations above mentioned may be made in a progressive die all on the same machine as will be more fully described in my copending application above referred to.

15 In order to acquaint those skilled in the art with the manner of constructing the radiator of my invention according to the present novel method, I shall now describe with the aid of the accompanying drawings the preferred manner of carrying my invention 20 into effect.

In the accompanying drawings:

Figure 1 is a perspective view of a flat strip of metal from which the tube half is formed;

25 Fig. 2 is a perspective view of the strip or sheet after the initial corrugating or ridging steps;

Fig. 3 is a plan view of the corrugated strip after the second or slitting operation;

30 Fig. 4 is a transverse longitudinal section of the corrugated strip taken on line 4—4 of Fig. 3;

Fig. 5 is a transverse section taken on line 5—5 of Fig. 3;

35 Fig. 6 is a plan view of the strip after the next stage of operations which includes the step of pinching the intermediate parts of the corrugations or ridges and simultaneously pressing out the central longitudinal portion of the strip to form a gutter or channel;

Fig. 7 is a longitudinal sectional view taken on the line 7—7 of Fig. 6 across the wings or water legs;

40 Fig. 8 is a similar view taken on line 8—8 of Fig. 6 across the pinched ends;

Fig. 9 is a transverse section taken on line 9—9 of Fig. 6 through one of the wings or water legs and the adjacent marginal loops;

45 Fig. 10 is a plan view of the strip or tube half in the next stage of progression, the lateral wings or water legs are brought more nearly to form, that is, slightly more compressed and the outer edges brought closer together, in fact, into contact;

Figs. 11 and 12 are sections taken on corresponding lines as indicated on Fig. 10;

50 Fig. 12^A is a transverse sectional view of one of the lateral channels in my novel half tube construction illustrating one of the steps involved in the forming of same;

Fig. 13 is a plan view of the final stage of the tube half, the joining margins just inside the loops being flattened down into a 65 common plane, the tops of the water legs

or lateral projections being squared up, the ends thereof pinched closely into contact and the metal between the water legs being flattened down;

Figs. 14, 15, 16 and 17 are sections taken 70 on the correspondingly numbered lines in Fig. 13;

Fig. 18 is a face view or front elevation of a portion of the assembled core;

Fig. 19 is a sectional view illustrating the 75 cross section of the semi-hexagonal corrugation employed in the marginal loops of my construction;

Fig. 20 is a sectional view illustrating how 80 the ends of the channel projections are pinched together; and

Fig. 21 is a more or less diagrammatic view illustrating the cross-section of a channel in my construction.

Whereas, in the accompanying drawings 85 the corners where the sheet is bent are shown as being sharp, it is to be understood that I avoid as much as possible all sharp corners and even if the inner side of a bent portion of the sheet is sharp it will be understood that the outer surface thereof does not assume an absolutely sharp corner. Similarly, where the metal is folded together, it will be understood that absolute meeting of the edges is not essential since 90 all edges are dipped in solder which joins and seals these edges.

Whereas, I shall describe herein the preferred method of procedure in making up the radiator core of my invention, it is to be 100 understood that the order of steps which I shall describe may be considerably varied. In fact, I have constructed the radiator of my invention according to the steps herein described but varied considerably as to 105 the order in which they are accomplished.

I employ as suitable stock or metal a strip 1 of brass, bronze, or copper, which is formed into a continuous gutter or channel with joining margins and ornamental and 110 spacing loops at the edges which is cut into suitable lengths and these lengths are placed face to face to form a tube. According to the preferred mode of procedure, I bend up corrugations 2 from the plane of the strip 1. These corrugations are preferably semi-hexagonal in shape with flat tops and flat sides, but can be any other shape, the various angles of bending being substantially 60°, the tops, bottoms and sides of the 115 corrugations being all of substantially equal length. It is well known that the sides of an inscribed regular hexagon are equal to the radius of the circumscribing circle. Hence, each of the flat sides of a corrugation are equal to half the distance across 120 the base of the corrugation which base corresponds to the diameter of the circumscribing circle. I shall designate the portion of the sheet lying between corrugations by the 125

letter "A" and the three sides of the corrugations, respectively, B, C, and D.

This matter of corrugating the strip 1 may be performed in corrugating rolls as I shall describe elsewhere.

After the strip has passed through the corrugating rolls it is then slit as indicated in Fig. 3 by slits 3 and 4 adjacent the edges, these slits extending across the walls 10 B, C, and D of the corrugations 2 near the margins of the sheet. Thus, the ornamental loops 5 and 6 are cut from the sheet and being already formed to the right pitch, they are not thereafter altered.

15 The slitting of the corrugations at 3 and 4 is preferably performed upon a punch press with suitable dies. In order to make the slits 3 and 4 it is necessary that the metal be sheared off, and to do this, the edges 20 of the metal just inside the loops 5 and 6 is depressed as indicated in Figs. 3 and 5. The middle part of the transverse corrugations 2 still retain the shape of the original corrugations and of the loops 5 and 6. It 25 is to be understood that the slitting operation may precede the corrugating or folding operation if desired. However, I find it more desirable to slit the corrugations after they are formed than to slit the sheets before 30 the corrugations are formed, since this mode of procedure permits the loops to be formed integral with the main body of the sheet and hence to be brought to exact form without any interference with the slitting operation, 35 and such distortion that occurs from the slitting operation does not affect the accuracy of the folding or corrugations. It is to be understood furthermore that the slitting operation may be performed simultaneously 40 with the corrugating operation if desired.

The next stage of operation according to the preferred mode of procedure is to form the channel by offsetting the central longitudinal part of the sheet with respect to the 45 margins, which margins remain relatively in the same position as the original sheet 1 before the corrugations 2 are raised therefrom. In the present specification and in the claims I employ the term "the original plane of the 50 sheet" to designate a certain reference plane which corresponds in Fig. 2 to the plane of original sheet 1 and also the plane of the faces A between corrugations 2. These faces A which I may term "the bottoms of 55 the corrugations" still lie in the plane of the original sheet in the stage represented by Figs. 3 to 5.

The next step or stage of operations involves two actions. One is the fundamental 60 action of forming a channel or trough longitudinally of the sheet by offsetting the central part of the sheet longitudinally into a plane parallel with the original plane of the sheet. This forming of a gutter or channel 65 is necessary in order to form the ultimate

tube as the thickness of the tube when finished is equal to twice the amount of offset of the bottom of the channel. In performing this operation of offsetting the bottom of the channel with respect to the original 70 plane of the sheet, it is necessary to observe the requirement for a sealing margin at each edge just inside of the ornamental loops. Also, in this operation of forming the gutter or channel, it is necessary to bend the 75 metal of the sheet across the corrugations. Also, since these corrugations between the slit ends which define the loops are to be formed into closed pockets or water legs, it will be necessary to seal or close these slit 80 ends. This combined action of forming the channel or gutter, bending across the corrugations and sealing the ends of the corrugations, I perform by a relatively simple but effective operation as follows:

I arrange to close the ends of the corrugations by pinching together the upper parts of the corrugation at each end where it is slit free of the loops. Now, since this pinching together will result in a fold or seam 85 which preferably lies in a plane at right angles to the original plane of the sheet and transverse to the longitudinal axis of the sheet, and since these pinched together walls are a continuation, or, in fact, merely the 90 outer ends of the side walls of the transverse corrugations between the loops, I form these corrugations so that they will be of less thickness than the face C of the original corrugation, and will have vertical side walls 95 parallel to each other and parallel to the plane of the pinched together walls. The plane of the seam where the pinched together ends engage each other, lies substantially centrally of the original corrugations 100 105 and centrally of the squeezed together corrugations which begin to assume the form of pockets. At the same time that the ends are pinched together and the side walls are squeezed towards each other, the bottom of 110 the channel is depressed so as to form the gutter and sealing margin.

Referring now more particularly to Figs. 6 to 9, inclusive, which show the sheet after this compound operation of depressing the 115 bottom of the gutter, squeezing together the top of the intermediate part of the corrugations and pinching towards each other the walls at the ends thereof, it will be seen that the original loops 5 and 6 are not disturbed. Also, the bottoms A are still of the 120 original width completely across the sheet. However, these bottoms A have now been divided into five separate parts, namely, the middle or bottom part 10, two sloping faces 125 11 and 12 which form the ends of the tube in the finished form, front and rear, and the outer faces 13 and 14.

The parts 13 and 14 of original face or bottom A comprise in reality two parts, 130

namely, an outer part, the width of the loops 5 and an inner part which is a part of the sealing margins, which extends from the inner edge of the loops to the bend formed between the parts 11 and 13. By the initial corrugation illustrated in Fig. 2, the original sheet 1 was diminished in length by one-quarter, in other words, by the width of one of the faces A, B, C or D. Since face 10 A remains unchanged in width and therefore occupies one-third of the corrugated sheet, the other two-thirds of the length of the corrugated sheet is the space occupied between points 15 and 18 as viewed on Figs. 15 4 and 19. In other words, assuming that the semi-hexagon is circumscribed by a semi-circle, the side A is of a width substantially equal to the radius of the circumscribing semi-circle, while the space occupied by the 20 corrugation is equal to the diameter of the circumscribing semi-circle. The corrugations 20 have been reduced in width as shown in Figs. 6 to 9, inclusive, by the action of dies which squeeze the top parts of these corrugations together into a narrow transverse projection or wing having substantially vertical walls as is apparent from Fig. 7. These vertical walls 21 and 22 are of a width, that is, a vertical width, as viewed in 30 Fig. 7, substantially equal to one-half the radius of the circumscribing circle above referred to. These vertical walls 21 and 22 were formerly part of the side walls C and D of the corrugations 2, the rest of the side 35 walls of the corrugations now appearing in slanting walls 24 and 25 which go to define parts of the end and bottom walls of the gutter. The vertical walls 21 and 22 are integral with the walls 21' and 22' at the ends 40 of the pockets 20, where these walls 21' and 22' are pinched together substantially in contact as will be apparent from Fig. 8. In the process of thrusting out or offsetting the bottom of the gutter, it was necessary to 45 make four bends, namely, the bends indicated at 27, 28, 29 and 30, as viewed in Fig. 9. In forming these bends, the pinching together of the ends of the pockets 20—20 assisted materially in defining the region 50 where the corrugations would be bent. That is to say, the ends of the pockets where they are pinched together are triangular. Where the base of the triangle joins the full width of the pocket 20 there is a gentle bend as indicated at 31' and 32' in Fig. 9. There is 55 no bend which corresponds exactly or noticeably with the bend along the lines 27 and 30, since the triangular end parts of the pockets taper downwardly on substantially a straight line. There is, I believe, a very slight stretching of the sheet metal where the base of the triangular end part joins the rectangular middle part of these sockets since I find that these pinched together ends extend slightly under the loops 5 and 6 as indicated at 60 65

in Fig. 9. It will be noted particularly in Figs. 7 and 9 that the tops of the pockets 20 now lie above the tops of the loops 5 and 6, the vertical walls 21 and 22 which are of the same height as the vertical walls 21 and 22 and, in fact, are merely continuations of the same, are of the same height, namely, one-half of the radius of the inscribing circle. It is necessary in order to finish the pockets to close together tightly these 70 walls 21 and 22, or at least tight enough so that they will be closed by solder.

The next stage or step which is illustrated in Figs. 10, 11 and 12, comprises merely a squeezing together of the pockets 20 along the sides 21 and 22 and a squeezing together of the end portions 21' and 22' thereof. These walls are brought substantially into contact so that the final stage of squaring up will bring these walls 21' and 22' substantially into contact. In the stage illustrated in Fig. 10, the side walls 21 and 22 of the corrugations 20 are brought slightly closer together with a resulting bulge upwardly of the upper wall 23. The walls 21 and 22 are not vertical at this stage, but are closer together at the top than at the bottom so that in the final forming operation illustrated in Figs. 13 to 17, inclusive, the bringing down into the horizontal of the walls 24 and 25 will throw inward slightly the lower ends of the walls 21 and 22 and bring them into parallelism substantially normal to the original plane of the sheet. In the same manner the bringing down of the walls 24' and 25' which are really continuations of the walls 24 and 25 will serve to close together the walls 21' and 22' of the ends of these pockets. Fig. 12^a illustrates the above condition.

In the final stage or step, the pockets 20 are squared up, the top walls of the corrugations are pressed flat into a plane substantially the same as the plane of the tops of the loops 5 and 6 and the walls 24 and 25 and 24' and 25' are all brought down into the plane of the adjacent part, so that the flat wall 31 forms the bottom, this entire length occupying substantially five-sevenths of the length of the tube and the corrugations occupying substantially only two-sevenths of the length of the tube. The gutter which forms the half of the tube is now well defined, the margins 32 and 33 appear plainly and they lie in the same plane as the original plane of the sheet. The end walls 11 and 12 are also clearly defined. A portion of the sealing margin is formed of the walls 24' and 25' which have been brought into the same plane as the original bottoms of the corrugations. The pinched together ends 21' and 22' in the final finished stage, illustrated in Figs. 13 to 17, inclusive, the length of the metal is distributed as follows:

Referring now to diagrams Figs. 19, 20

and 21, and assuming that the metal has no appreciable thickness, the various lengths are taken up as follows:

This assumption of no thickness in the metal does not introduce any material errors. The entire length of the sheet was taken up in the corrugating stage by the faces A, B, C and D of successive corrugations. As previously explained, this resulted in shortening the sheet one-fourth. The remaining three-fourths are distributed in three equal parts, namely, one part or one-third remains in the original face A which extends completely across the finished tube without alteration, the remaining three-fourths of the original length are now disposed in two-thirds of the finished tube. In the loop, the disposition is as follows:

Sides B, C and D of the finished loops are each of a length in the linear direction of the tube, the same as the length of the face A. Since they are disposed as the three sides of a regular hexagon they occupy longitudinally only the diameter of the circumscribing circle, the radius of which is equal to the length of the face A.

In the pinched together ends (see Fig. 20) the metal which is shown in Fig. 9 in the faces B, C and D has now been disposed in faces E, F, G and H. The faces E and F are substantially the same length as the faces B and D, while the sum of faces G and H is equal to C. In other words, the faces G and H are merely face C folded into a bight. This bight extends upwardly for a distance substantially equal to one-half the radius of the circumscribing circle. At the central part where the full width of the pocket 20 is formed, the metal previously disposed in the faces B, C and D is now disposed in faces I, J, K, L and M. Of these five faces, the sum of faces I, K and M is equal to the diameter of the circumscribing circle, in other words, is equal to the sum of faces B and D, while faces J and L together are equal to the length of face C, that is, the length of the radius of the circumscribing circle. Hence, the extent or height of the projection 20 upon the bottom of the gutter or channel is substantially one-half of the radius of the circumscribing circle and the depth of the gutter is slightly less than one-half the radius of the circumscribing circle.

After these tube halves are properly formed, they are assembled as indicated in Fig. 18, so that the loops are in register with each other and form an ornamental front at back and rear with the water legs substantially in contact. The group of assembled tubes is held in a frame and the front and rear joining margins and loops are dipped in solder to a depth sufficient to seal the sealing margins and to join together the loops at the front but not deep

enough to join together the water legs. The resulting structure has remarkable resiliency and strength in addition to excellent efficiency. The tubes will stand repeated freezing without injury. The water channels 70 are large and straight. The metal is used to a maximum advantage.

I do not intend to be limited to the details above shown and described, nor do I intend to limit my invention to the order of the 75 steps above recited, except as the same is particularly stated in the appended claims. The longitudinal channeling may be formed ahead of or simultaneously with the cross corrugation instead of after the same, which 80 I have above described.

I claim:—

1. The herein described process for forming a radiator half tube out of a strip of sheet metal comprising, corrugating said 85 strip with equally pitched transverse ridges, slitting alternate ridges to free the central part of the transverse ridges from the marginal portions, moving the longitudinal central portion of the corrugated strip 90 out of the prior plane thereof to form a gutter, and closing together the slitted ends of the transverse ridges.

2. The herein described method of forming a tube half from a strip of sheet metal which comprises, raising flat topped ridges or folds 95 transversely on the strip, slitting the ridges adjacent the margins of the strip to form free loops and pinching together the ends of the ridges or folds where they have been 100 slitted free of the loops.

3. The herein described process of forming a tube half from a strip of sheet metal which comprises raising flat topped ridges or folds transversely of the strip, slitting the ridges adjacent the margins of the strip 105 to form free loops along the margins, pinching together the slitted ends of the ridges or folds and raising the central longitudinal part of the strip to form a gutter.

4. The herein described process of forming a tube half from a strip of sheet metal which comprises raising flat topped ridges or folds transversely of the strip, slitting the ridges adjacent the margins of the strip to form free loops along the margins, pinching together the slitted ends of the ridges or folds and raising the central longitudinal 115 part of the strip to form a gutter, and forming flat joining margins for the strip just inside of the line of slits along each margin of the strip.

5. In the herein described process of forming a tube half from a strip of sheet metal, the process of forming ornamental connecting loops on the margins of the sheet which comprises, forming semi-hexagonal corrugations across the width of the strip or sheet, slitting the corrugations near the margin of the sheet to define free loops along the mar- 125 130

gin, and pinching together the slit edges of the corrugations to form closed pockets.

6. The herein described process comprising, forming flat sided semi-hexagonal corrugations transversely of the sheet, slitting alternate ridges along three sides to form free semi-hexagonal loops, and squeezing together the intermediate portion of said alternate ridges or corrugations to bring a portion of the metal into a common plane substantially parallel to but out of the plane of the main part of the sheet, closing together the ends of said ridges or corrugations and forming joining margins in the plane of the main part of the sheet.

7. The method of forming a tube half comprising, corrugating a sheet by repeated transverse bends at equally spaced points along the length of the sheet as follows, at point 1 counterclockwise 60° , at point 2 clockwise 60° , at point 3 clockwise 60° , at point 4 counterclockwise 60° , and then repeating the above schedule along the length of the sheet; slitting the corrugated strip from points 1 to 4 along both margins to form loops from the outer ends of the corrugations; closing together the slit edges of the corrugations to form lateral pockets; and raising the longitudinal median part of the strip to form a gutter.

8. The method of forming a tube half which comprises; corrugating a strip by a series of 60° bends to raise a series of semi-hexagonal ridges from the plane of the sheet or strip; slitting said ridges on lines parallel to and spaced from the margins of the strip or sheet; raising the central longitudinal part of the sheet with the ridges thereon above the plane of the sheet to form an inverted gutter, squeezing towards each other the upper parts of the side walls of the ridges; and pinching together the slit ends of the ridges to close the pocket, and to form a flat continuous joining margin in the plane of the sheet along the sides of the sheet inside of the loops.

9. The method of forming a tube half from a strip of sheet metal which comprises; corrugating the strip to raise a series of semi-hexagonal transverse ridges from the plane of the strip; slitting said ridges to define semi-hexagonal loops along both margins of the strip; raising the central part of the sheet and the ridges to form a gutter; squeezing together the side walls of the ridges to reduce the thickness of the ridges; pinching together the slit ends of the ridges to form closed pockets from said ridges; pressing down the ridges to bring their tops into substantially the level of the top of the loops, and pressing down into the plane of the strip the metal adjacent the pinched ends to form a sealing flange at each margin within the loops.

10. The method of forming a tube half

which comprises; corrugating the strip to form flat sided and flat topped ridges above the plane of the strip, said ridges having their tops lying in a plane parallel to the plane of the strip; slitting said ridges to define loops along both margins of the strips; squeezing together the top parts of the side walls of the corrugations into parallel planes at substantially right angles to the plane of the sheet or strip and at the same time raising the central longitudinal part of the sheet or strip with the corrugations, whereby the top parts of the corrugations are raised and reduced in thickness, and at the same time an inverted longitudinal gutter is formed; holding down the ends of the ridges where they have been slit away from the loops and simultaneously pinching the tops of them together; then pressing down the tops of the corrugations into substantially the plane of the tops of the loops, and pressing down the lower parts of the side walls of the ridges into the plane of the bottom of the gutter, and pressing down the side walls of the ridges adjacent the pinched together ends into the original plane of the sheet to form sealing margins along both edges.

11. The method of producing a radiator core section consisting in forming a tube of similar halves with a straight water passageway from end to end while forming the same from a strip to provide a central channel portion and lateral corrugations with integral laterally deflected loops on an edge of the channel portion, separating the loops therefrom by a slit with the lateral corrugations all lying in register with the loops and taking up the necessary linear surplus of metal to compensate for the metal required for the laterally deflected loops.

12. In the method of forming a radiator tube from a strip of sheet metal, the combination of the following operation: slitting the metal along the edge of the strip, forming the longitudinal central portion of the strip into a channel, shrinking the sheet longitudinally to form loops from said slit portions along the edges and water legs or corrugations along the lateral sides of the channel and joining two half tubes to make a tube.

13. In the method of constructing a radiator core section, the combination of the following operations, slitting the blank adjacent each edge at regular intervals, longitudinally folding the blank to form an intermediate trough and transversely folding the outer portions of the blank along each of the slits to form depending loops of sheet metal extending laterally from the plane of the original sheet and below the level of the corrugated trough bottom.

14. In the method of forming a radiator core section, the combination of the follow-

ing operations; slitting the blank adjacent each edge, longitudinally folding the blanks between the rows to form a trough having an irregular bottom and side walls, folding the portions outlying the slits to form outlying depending loops of sheet metal at each slit, taking up the excess of metal in the intermediate portion lying between the slit and the trough edges by forming closed transverse loops, then placing the two like formed units face to face to form a flattened tube, each trough forming a half thereof, and sealing the tube on either side by soldering the contacting metal surfaces of adjacent halves together.

15 16. In the method of making a radiator core wall, slitting a sheet of thin metal along each edge, then folding the blank to form an intervening longitudinal trough between the slits, the said trough being crimped transversely, folding the outer portions of the blank outside each of the slits to create loops of sheet metal extending beyond the corrugated trough bottom.

20 17. The method of forming a radiator core section which comprises, slitting a blank along its edges, offsetting the central part of the sheet between the rows to form a trough with outer flanges or joining margins, folding the outer edges of the strip outlying the slits to form depending loops of sheet metal at each slit, taking up the excess of metal between the slits and the trough edges by forming closed transverse pockets, then placing the two like formed units face to face to form a flattened tube of which each trough forms a half, and then sealing the tube by soldering the contacting metal surfaces of the respective units together.

25 18. The method of making a radiator core section the following steps, slitting a sheet of metal at intervals along its edges, longitudinally forming the blank to form an inverted trough, crimping the said trough transversely of its length to form closed pockets along the sides of the trough and to create laterally extending open loops of sheet metal along the edges and soldering two halves together to form a tube.

30 19. The method of manufacturing a radiator core section consisting in first subjecting each of a pair of metal sheets to the following operations; folding each sheet to form a central longitudinal trough in a single plane having a transversely corrugated bottom and having side walls, and sealing margins, transversely folding the edges of the sealing margins to form closed pockets of said corrugations, severing and depressing integral loops from the edge of the metal and transverse corrugations, then placing both formed sheets face to face to cause the sealing margins to be brought into contact and then soldering said sealing margins.

35 19. The method of manufacturing a sheet metal radiator core section involving the following steps; folding each of a pair of like metal sheets to form longitudinal extending troughs from each sheet, transversely corrugating the trough bottoms, slitting and laterally deflecting integral portions from the edge of the metal sheets in a regular pattern, placing the so formed sheets face to face with the edges thereof in contact and joining said edges by soldering.

40 20. The method of forming radiator tubes from strips of sheet metal comprising the following steps, cutting and forming free loops in a regular cellular pattern from the edges of the sheet or strip, forming a longitudinal gutter with flat joining margins and with transversely extending closed end pockets or water legs to take up the same amount of metal as is employed for said loops, and joining complementary gutters along said joining margins to form tubes.

45 21. The method of forming a sheet metal radiator tube which comprises forming slits along an edge of a sheet metal strip, offsetting the fitted portions adjacent the edge to form loops and simultaneously forming lateral corrugations in the body of the metal adjacent the loops so that the metal may be substantially equally foreshortened across the full width of the metal strip.

50 22. The method of forming a radiator tube half from a strip of sheet metal which comprises the following steps, deflecting laterally integral parts of the sheet and slitting the same to form free loops along the outer margins and to form closed pockets or water legs along the intermediate central part, and equally foreshortening the strip across the full width thereof by said loops and said pockets.

55 23. The method of forming a radiator tube half from a strip of sheet metal which comprises the following steps, deflecting laterally integral parts of the sheet and slitting the same to form free loops along the outer margins and to form closed pockets or water legs along the intermediate central part, and equally foreshortening the strip across the full width thereof by said loops and said pockets, and forming a longitudinal median depression or gutter with flat joining margins at each side thereof.

60 24. The method of forming sheet metal tubes out of sheet metal strips which comprises forming slits adjacent one edge of the strip, bending the slitted portion laterally to form an ornamental loop or fin for the front of the tube and corrugating the body of metal transversely to take up the surplus metal which is caused by the lateral bending of the slitted portion.

65 25. The method of forming sheet metal tubes out of sheet metal strips which comprises forming slits adjacent one edge of

the strip, bending the slitted portion laterally to form an ornamental loop or fin for the front of the tube and corrugating the body of metal transversely to take up the surplus metal which is caused by the lateral bending of the slitted portion, and closing the ends of said corrugations to form water legs or pockets along the sides of the tube.

26. The method of forming a radiator tube comprising the following steps, slitting a strip of metal along one edge of the same, forming a transverse fold in the body of the metal adjacent the slit to provide a surplus of metal in a longitudinal direction along the slitted portion and bending said slitted portion laterally to form an ornamental loop.

27. In the method of making a radiator tube out of a strip of sheet metal the following steps, namely, slitting the metal along the edges of the same to form loops integral at their ends with the remainder of the metal, forming a gutter longitudinally of the strip, corrugating the strip laterally across the gutter and adjacent the slitted portion completely transversely of the gutter portion, and bending the slitted portions along the margins laterally to form ornamental loops.

28. In the method of forming a radiator tube from a strip of sheet metal the following steps, namely, slitting the strip of metal adjacent one edge thereof, then longitudinally foreshortening the strip by bending the slitted portion laterally and by forming a crease transversely of the body of the strip, forming a gutter lengthwise of the strip of sheet metal, said gutter having joining margins along its edges, then collapsing the edges of the transverse creases to close the same securely at the edges to form pockets adjacent the loops.

29. In the method of forming a radiator tube the following steps, namely, slitting a strip of sheet metal along one edge of the same to form loops or fins, offsetting said loops or fins laterally to form ornamental figures according to a regular pattern, and simultaneously foreshortening the sheet between the loops to form closed water legs or pockets.

30. In the method of forming a radiator tube the following steps, namely, slitting a strip of sheet metal along one edge of the same to form loops or fins, offsetting said loops or fins laterally to form ornamental figures according to a regular pattern, and simultaneously foreshortening the sheet between the loops to form closed water legs or pockets, and forming a gutter or longitudinal depression in the central part of the sheet, said gutter having joining margins.

31. In the method of forming a radiator tube comprising the following steps, namely, slitting a strip of sheet metal along one edge of the same to form loops or fins, offsetting

said loops or fins laterally to form ornamental figures, and simultaneously foreshortening the sheet between the ends of a loop to form lateral corrugations, forming a gutter in a central part of a sheet with flat joining margins and placing a plurality of strips thus formed with the gutters facing each other and the margins in contact and dipping the lateral loops and the margins in solder to close the seam along said margins.

32. The method of forming automobile radiator cores consisting in forming tubes by pressing similar halves into a central channel portion to form a straight water passage from end to end, forming the same with lateral corrugations having closed ends by pressing the metal together in spaced relation to the edges of the halves, slitting the halves, deflecting loops laterally beyond said channel portion on each edge of said portion and separating the same therefrom by a slit so as to dispose the lateral corrugations in register with the loops at the same side, and causing the loops and corrugations to take up the same length of metal whereby the corrugations will comprise the necessary linear surplus of metal to compensate for the metal required for the laterally deflected loops.

33. The method of manufacturing a radiator core section consisting in first subjecting each of a pair of independent metal sheets to the following operations; folding each sheet to form a longitudinal trough in a single plane having a transversely corrugated bottom and having side walls, and sealing margins, transversely folding the edges of the sealing margins to form closed pockets of said corrugations, severing the edges of the sheets at spaced points, depressing integral loops from the severed edges of the metal, then placing both formed sheets face to face with their troughs toward each other, to cause the sealing margins to be brought into contact and then joining said sealing margins.

34. The method of forming a radiator tube from a strip of sheet metal which comprises the following steps, slitting and deflecting laterally integral parts of the sheet to form free loops along the margins, forming closed pockets or water legs along the intermediate central part between the slits, and equally foreshortening the strip across the full width thereof by said loops and said pockets.

35. The herein described process for forming a radiator half tube out of a strip of sheet metal comprising corrugating said strip, slitting alternate ridges to free the central part of the transverse ridges therebetween from the marginal portions, and contracting the strip inwardly of said marginal portions.

36. The method of forming a radiator tube from a strip of sheet metal including corrugating said strip with transverse ridges,

slitting the strip longitudinally adjacent alternate ridges to free the marginal portions from the central portions to form loops, and shrinking the ends of the corrugations adjacent to the loops to close the ends of adjacent ridges.

37. The method of forming a radiator tube from a strip of sheet metal including corrugating said strip with transverse ridges,

10 slitting the strip longitudinally adjacent alternate ridges to free the marginal portions from the central portions to form loops and shrinking the metal of the strip between alternate ridges where slit to provide substantially flat marginal portions substantially in the plane of the alternate loops, and joining complementary half tubes thus formed along said marginal portions and at the loops.

15 38. The method of forming a radiator tube from a strip of sheet metal including corrugating said strip with transverse ridges, slitting the strip longitudinally adjacent alternate ridges to free the marginal portions from the central portions to form loops and gathering the ends of alternate ridges in line with alternate loops to take up linear surplus of metal and provide narrow longitudinal flat portions at the ends of the ridges inwardly of the slits and loops for contact between and joining complementary half tubes.

20 39. The herein described method of making radiator cores consisting in corrugating a strip of sheet metal transversely to provide equally and oppositely pitched transverse ridges, slitting the strip longitudinally near the margins thereof in line with alternate ridges to form free loops with flat, narrow straight portions between the loops and ridges, and joining complementary sections

25 thus formed at the narrow portions and tops of the ridges of said loops.

30 40. The herein described method of making radiator cores consisting in corrugating a strip of sheet metal transversely to provide equally and oppositely pitched transverse ridges, slitting the strip longitudinally near the margins thereof in line with alternate ridges to form free loops with flat, narrow straight portions between the loops and ridges, and contracting the strip opposite

35 said alternate loops and at the ends of aligned ridges to provide substantially flat portions at the back, forming soldering connections together with loops between complementary sections thus produced.

40 41. The method of forming a radiator tube from a strip of sheet metal which comprises the following steps, slitting and deflecting laterally integral parts of the sheet to form loops along the margins and to form closed pockets along the intermediate central part, and shrinking lengthwise portions between the pockets and loops.

45 42. The method of forming a radiator tube from a strip of sheet metal which com-

prises the following steps, slitting the sheet at spaced points and deflecting laterally integral parts of the sheet thus formed to form loops along the margins and to form transverse pockets along the intermediate central part, and shrinking lengthwise portions between the pockets and loops, to provide flat margins for connection with complementary margins of another strip and close the ends of the pockets.

70 43. The herein described process for forming a radiator half tube out of a strip of sheet metal comprising slitting alternate ridges formed by corrugating the strip to free the central part of the transverse ridges therebetween from the marginal portion and shrinking joint margins between the ends of the transverse ridges and the marginal portions to close the ends of the ridges and take up linear surplusage of the metal.

75 44. In the method of forming a radiator tube from a strip of sheet metal, the combination of the following operations; slitting the metal along the edge of the strip at spaced points, forming the longitudinal central portion of the strip into transverse ridges and marginal loops outside of the slits, and shrinking portions of the sheet longitudinally to form jointing margins throughout the length of the strip inside the slits.

80 45. The method of forming a radiator tube comprising the following steps, slitting a strip of metal along one edge of the same, forming a transverse fold in the body of the metal adjacent the slit to provide a surplus of metal in a longitudinal direction along the slitted portion, gathering said surplus metal, and bending said slitted portion laterally to form an ornamental loop.

85 46. The method of forming a radiator tube comprising the following steps, slitting a strip of metal along its edges, forming transverse corrugations therein and shaping the portions outwardly of the slit to form loops, and shrinking narrow marginal portions between the corrugations and loops to provide portions by which complementary strips so formed may be soldered together in conjunction with the loop ridges.

90 47. The herein described method of making radiator core tubes comprising the following steps; slitting the edges of the sheet to free portions for forming integral loops, shrinking the sheet endwise to form the slit parts into loops and to form the central parts into corrugations taking up the same length of material as the loops, and gathering the edges of the material into flat jointing margins.

95 48. The method of producing a radiator consisting in forming a tube of similar halves with a straight water passageway from end to end while forming the same from a strip to provide a central channel

portion and lateral corrugations with integral laterally deflected loops on an edge of the channel portion, separating the loops therefrom by a slit with the lateral corrugations all lying in register with the loops and taking up the necessary linear surplus of metal to compensate for the metal required for the laterally deflected loops, joining the tubes and assembling the radiator from the built up tubes.

49. The novel method of forming a tube section from a strip of sheet material consisting in slitting the metal, forming channels therein, compressing the channel ends and depressing the marginal portions of the strip adjacent the channel ends to form free loops at the ends of the channels.

In witness whereof, I hereunto subscribe my name this 6th day of November, 1922.

FRED M. OPITZ.
